COAT SLEEVE FORM

Mark M. Uhley, Sioux Falls, S. Dak.

Application August 13, 1937, Serial No. 159,006

2 Claims. (Cl. 223—72)

This invention relates to improvements in coat sleeve forms, and more particularly to such forms as used in displaying garments or the like.

Heretofore in displaying coats for men, women, and children it has been customary to distend the sleeves of such garments by inserting a filler or wadding composed of tissue paper or other material. It is now desirable to devise a form by which the sleeves of a garment may be displayed in the form which the garment assumes when the latter is placed upon the wearer, and to this purpose I have provided a novel type of sleeve form, which may be quickly attached to a display dummy.

The primary important object of this invention is to provide a device of the above character which will hold a coat sleeve in a substantially natural distended form during the display thereof.

Another important object of this invention is to provide a device of the above character in which a minimum of padding is required, but which will present a life-like appearance in use.

A further important object of this invention is to provide a device of the above character in which same may be readily attached to or detached from the torso of the model with which same is used.

A still further important object of the invention is to provide a device of the above mentioned character which is of simple construction and one which may be readily and cheaply manufactured and placed upon the market at a reasonable cost. These and other objects and advantages will be apparent throughout the following description and drawing.

In the drawing:

Fig. 1 is an elevation of the preformed embodiment of the form which is to be inserted within the left sleeve of a coat or other garment;

Fig. 2 is an elevation of the body portion of the form with the padding and covering removed as same appears when looking at the inside face or that portion which lies adjacent the body of the display dummy;

Fig. 3 is an edge elevation of the body of the form with the padding and covering removed, when viewed from the rear;

Fig. 4 is a section on line 4—4 of Fig. 1; and Fig. 5 is an elevation of a modified type of coat sleeve form with the padding removed.

Referring in detail to the drawing, 1 designates a body member composed of wall board or other suitable light weight material, having the general outline of a coat sleeve. In this particular in-

stance the body is formed to be inserted within the left sleeve of a coat or similar garment to be displayed. The body 1 is provided with a concave front edge 2, a convex rear edge 3, a straight lower end 4, and an arcuate shaped 5 upper end.

Secured to the inner side face of the body member 1, intermediate the upper and lower ends of the latter and adjacent its rear convex edge 3, is a built-up off-set or elevated member 6, composed of laminations 7 and 8, the latter having their upper and lower free ends tapered downwardly and outwardly therefrom to merge into the adjacent portions of the body member.

The built-up off-set or elevated member 6 is formed to simulate the muscle or enlarged upper portion of a human arm when viewed in front elevation.

Disposed over the body member 1 and the built-up portion 6 thereof is a uniform layer of cotton, felt, or other suitable material 9 to serve as a padding between said portions and the covering 10 of any suitable material, which latter may be secured thereabout in any suitable manner. Secured to the upper arcuate shaped end 25 of the form is a tab 11 by which the form may be readily connected to the torso or body portion of a display dummy (not shown).

It is to be particularly noted that the built-up or elevated portion 6 has its rear edge of convex 30 curvature so as to conform to and align with the rear edge 3 of the body member, while the front or forward edge of the portion 6 terminates between the edges 2 and 3 of the body member and is of substantially ogee configuration when viewed 35 in plan.

Referring to the modified form of the invention as disclosed in Fig. 5, same consists of a body 12 of substantially the same design as the body 1 disclosed in Figs. 1 and 2, and is provided with 40 a built-up or elevated portion 13 of similar shape, disclosed in Figs. 2 and 3, except that said portion 13 is formed in one piece of any suitable material and connected to the body member 12.

In use the completed form disclosed in Fig. 1 is connected to the shoulder portions of a display dummy (not shown) by means of the tab 11, and it is to be understood that a similar form representing the right arm is to be connected opposite thereto, whereupon the coat is placed upon 50 the display dummy with the forms, such as described, disposed within the sleeves of the coat, so that said sleeves will be distended and displayed in a manner similar to the appearance had when the arms of a wearer are placed therein. 55

It is to be understood that the form of my invention, herewith shown and described, is to be taken as a preferred example of the same, and that various changes in the shape, size, and arrangement of parts may be resorted to, without departing from the spirit of my invention, or the scope of the subjoined claims.

Having thus described my invention, I claim:

- 5 1. A built-up sleeve form for display purposes, comprising a flat elongated body having front and rear edges, a laminated member secured to one side face of the body having its rear edge aligned with the rear edge of the body and its front edge terminating at a point intermediate the front and rear edges of the body, padding 10 material of substantially uniform thickness dis-
- 15

posed over the body and laminated member so as to be deformed by the latter, and a fabric covering completely encasing all of said parts.

2. A built-up sleeve form for display purposes, comprising a flat elongated body having front and rear edges, a member secured to one side face of the body having one of its edges aligned with the rear edge of the body and another of its edges terminated at a point intermediate the front and rear edges of the body, padding material disposed over the body and member so as to be deformed by the latter, and a fabric covering completely encasing the body, member and padding.
